UNITED STATES PATENT OFFICE.

STEVEN BEKER, OF CARO, MICHIGAN.

SHIP-TABLE.

1,108,318.

Specification of Letters Patent. Patented Aug. 25, 1914.

Application filed April 16, 1914. Serial No. 832,378.

To all whom it may concern:

Be it known that I, STEVEN BEKER, a subject of the King of Hungary, residing at Caro, in the county of Tuscola and State of Michigan, have invented certain new and useful Improvements in Ship-Tables, of which the following is a specification.

This invention relates to new and useful improvements in ship tables.

The primary object of this invention is to provide a table and platform construction especially adapted for use upon ship-board and so constructed as to maintain its uniform equilibrium regardless of the movements and rocking of the ship.

A further object is to provide an eating table and a platform for diners all suspended for maintenance at a constant level for preventing sea-sickness or other effects produced by movements of the ship upon which the device is installed.

A still further object is to provide a constantly level platform suspended from a level mounting means for a table and providing a revoluble article support upon said table, while also affording a cushioning means in the event of any sidewise movement of the platform.

With these general objects in view and others that will appear as the nature of the invention is better understood, the same consists in the novel combination and arrangement of parts hereinafter fully described, illustrated in the accompanying drawings and pointed out in the appended claims.

In the drawings forming a part of this application and in which like designating characters refer to corresponding parts throughout the several views:—Figure 1 is a longitudinal central vertical sectional view through the device, and Fig. 2 is a top plan view thereof with one-half of the table top removed.

Referring more in detail to the drawings, the deck or flooring 10 is illustrated having the four legs 11 of a tubular neck 12 secured thereto for the purpose of mounting said neck thereabove. The passage 13 through said neck is flared at its upper portion 14 for receiving the mounting ball 15 therein.

A rod 16 depends from the ball 15 and is secured through the platform 17 while a plurality of braces 18 are connected between the rod 16 and said platform and whereby the platform is mounted swingingly upon the neck through the agency of said ball.

A table top 19 is mounted above the neck 12 upon the ball 15 by means of a plurality of brackets 20 and whereby as will be apparent any swinging of the platform is synchronous with the movements of said table top. The table top 19 is of dish-shape having an outer flange 21. The said table top is provided with an annular row of anti-friction balls 22 upon its upper surface and upon which are revolubly mounted the dish-shaped receptacle or table cover 23.

The deck 10 is provided with a plurality of coiled springs 24 arranged slightly beneath the level of the platform 17 and here illustrated as positioned at each corner portion thereof and which springs are adapted for cushioning the platform upon their engagement therewith upon any tilting movement of the platform.

The complete operation of the device will be apparent from this detail description in that the same being installed at any desired point upon ship-board, the diners or persons desiring to use the table are seated in chairs positioned upon the top of the platform 17 and in proximity to the side flange 21 of the table top 19. Any rocking of the ship will by reason of the suspending means herein described be incapable of rocking either the platform or the table top which will remain in their normal positions by the force of gravity. The dish or cover 23 is readily turned around upon the table top upon the bearings 22 for the purpose of bringing any portion thereof in front of any desired one of the occupants of the platform.

While the forms of the invention herein shown and described are what are believed to be preferable embodiments thereof, it is nevertheless to be understood that minor changes may be made in the form, proportion and details of construction without departing from the spirit and scope of the invention as set forth in the appended claims.

What I claim as new is:—

1. In combination with a deck, a neck having a central passage and rigidly secured to said deck, a ball freely mounted in the flaring upper end of said neck passage, a depending rod secured to said ball and extending through said passage, a platform secured horizontally to the lower end of said rod, a dish-shaped table top mounted upon said ball above said neck, and a revoluble dish-shaped cover mounted upon said table top.

2. A device of the class described comprising a deck member, legs rigidly mounted thereon, a neck upon the upper ends of said legs and having a passage therethrough with a flaring upper and lower end, a ball freely positioned in the upper flaring end of said neck, a depending rod secured to said ball and extending through said passage, a platform rigidly secured to the lower end 10 of said rod above said deck and extending in opposite directions between separate ones of said legs, a plurality of cushioning springs secured to said deck beneath said

platform, a dish-shaped table top mounted upon said ball above said neck, an annular row of anti-friction balls carried by the upper face of said table, a dish-shaped cover upon said table top rotatably mounted upon said balls. 15

In testimony whereof I affix my signature 20 in presence of two witnesses.

STEVEN BEKER.
